CLAIM

The ornamental design for a door draft stopper, as shown and described.

DESCRIPTION

FIG. 1 is a perspective view of a door draft stopper showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The door draft stopper is depicted with symbolic breaks in its length, indicating that the design is not limited to the specific length shown. The appearance of any portion of the door draft stopper between the break lines does not form part of the claimed design.
